DRUM SERIES PRINT MEMBER CONSTRUCTION
Clayton H. Clark, Mundelein, and Donald J. Stefanik,
Berwyn, Ill., assignors to SCM Corporation, New York,
N.Y., a corporation of New York
Original application Apr. 3, 1962, Ser. No. 184,820.
Divided and this application Aug. 23, 1965, Ser. No.
481,796

15 Claims. (Cl. 101—110)

This application is a division of copending application Ser. No. 184,820 filed Apr. 3, 1962, Patent No. 3,280,256.

This invention relates to a communications equipment drum printer primarily intended for use in high speed telegraphic and other data processing applications and particularly relates to construction of the printer drum.

The inventive drum type of continuously rotating page printer incorporates an inexpensive yet reliable and rugged drum construction, constituting the invention of this application.

Accordingly, a primary object of this invention resides in the provision of a novel drum printer drum construction.

A further object resides in the provision, in a continuously rotating drum printer, of a novel rotatable drum assembled from a plurality of rings of printing elements to provide lines of identical type faces extending from a start-of-line position to an end-of-line position on a page, each ring being of novel lightweight construction and maintained in accurate indexed assembly by means of clamping end plates and the frictional engagement between each adjacent ring, and specifically by providing such frictional engagement at the peripheries of adjacent rings.

In conjunction with aspects of the preceding object, still another object resides in providing the rings of printing elements on peripheral flanges of print wheels, each of which wheels has identical dual rows of all desired characters-to-be-printed on the printer and with the center lines of axially aligned, identical characters accurately spaced apart a predetermined distance and also accurately spaced from the adjacent edges of the peripheral flange one half of that predetermined distance and the axial width of the wheel peripheral flange being maintained to extremely minute tolerances.

Still another object resides in the provision of a novel drum printer print drum made from a laminated assembly of print wheel rings wherein each ring has a T-shaped radial cross-section with the circular peripheral portion of a ring carrying the printing symbols and constituting the cross flange of the T-section.

Other objects and novel aspects of the drum printer and its components will become apparent in conjunction with the description and the appended claims.

FIGURE 1 is a front perspective view of the printer, primarily to illustrate the general arrangement of printer components and therefore omitting many details which are illustrated in the following figures;

FIGURE 2 is a partially section elevation view showing the print drum with its drive gear, clock assembly, and bearing mounting and also illustrating the paper feed components;

FIGURE 3 is a side elevation view of one of the plurality of double typewheel discs from which the type drum is assembled;

2

FIGURE 4 is a layout detail view of a portion of the double type on the periphery of a typewheel; and

FIGURE 5 is a machine drawing detail, shown in section taken on lines 5—5 of FIGURES 3 and 4, and illustrates the drum assembly register slot and the requisite manufacturing tolerances for a disc with standard teletypewriter characters.

General

10 A perspective view of an exemplary teleprinter 102 is shown in FIGURE 1. This equipment was initially developed for high-speed telegraphic communication in conjunction with a complete send-receive system designed for keyboard sending and magnetic tape recorder sending, 15 page copy monitoring and page copy receiving. The entire system is more fully disclosed in copending parent application Ser. No. 184,820 to which reference may be made for details of printer structure and operation. The invention in this application pertains to the printer drum 20 construction and hence other details of the printer and its specific operation will not be described herein.

The printing mechanism, described briefly, employs a rotating drum composed of thirty-six double row type wheels, or a total of 72 rings of type, each ring having the 25 52 standard communication symbols. Other arrangements can be accommodated as desired. For example, for weather symbols, the drum has 76 rings of type, each ring having 52 conventional weather symbols. A print hammer is moved from left to right in front of the drum 30 under control of an escapement type spring-biased stepping mechanism and strikes the drum once per revolution for each character to be printed. The printing mechanism has a pulse clock mechanism which supplies a series of pulses to the printer electronics representative of drum 35 rotational position. Since each pulse represents a new character in the printing position, the pulses furnish information which allows the printer electronics to energize the print hammer electro-magnet as the desired character moves in front of the hammer. Characters on each ring 40 of type are placed in binary order according to the Baudot code for the character. Thus, each character is assigned a position in a 32-count, binary progression so that the printer electronics can compare an incoming character against the series of pulses that indicate the physical position 45 of the drum characters.

Printer mechanics

FIGURE 1 provides an over-all picture of the mechanical components of the type drum page printer 102 and the positional relationships of various components.

In general terms, the drum 704 includes, on its cylindrical periphery, a plurality of different lines of identical information symbols, 72 identical symbols (76 for a weather drum) constituting one line extending along the 55 cylindrical drum periphery parallel to the drum axis. The drum is continuously rotated by a printer motor (not shown) and is directly connected with a drum position clock wheel 706 to enable determination of the passage of each distinct line of type past a print station line by 60 related printer electronics which have been described in the aforementioned parent application. A print hammer carriage 708 can be spaced across in front of the drum surface, parallel to the drum axis, by an escapement spacing mechanism actuated by spacing solenoid 204 at the 65 right hand side plate. The carriage 708 is returned by a

carriage return mechanism seen at the left hand side of FIGURE 1, which is activated by the carriage return solenoid 308. Power for carriage return is derived through a clutch device driven by the printer motor.

A sheet paper, strip record medium is supplied from a paper roll 712 mounted between the frame end plates, to the rear of drum 704, the paper feeding over suitable guide devices (not shown), under and up past the front of the drum, passing between the drum 704 and the print hammer carriage 703 and under two, side edge guide fingers 713, one being shown in FIGURE 2. Paper feed is accomplished by two, solenoid stepped, pressure rolls under the drum which press the paper against two feed wheels at the ends of the print drum.

An ink ribbon 716 passes across the drum face parallel to the drum between the print hammer and the paper to transfer the typed impression from the drum to the page during a print operation. The ink ribbon assembly feed and reverse mechanism is conventional and will not be described. However, the ink ribbon 716 in this printer is rigged to always pass in a straight stretch across the front of the drum 704 parallel to the character spacing path of the print hammer, and the entire straight front stretch of the ink ribbon is lifted to a position in front of the hammer just prior to a printing action.

As shown in FIGURE 1, the printer components are mounted on a support structure including a thick base plate 718 having a slotted center bar 719 passing laterally from one side of the printer to the other and under the path of travel of the print hammer carriage. Two vertical side plates 720 and 721 are rigidly secured to the base plate 718 and provide the mounting structure for most of the printer components.

Drum assembly

Referring now to FIGURE 1 (also FIGURES 3-5), the print drum 704 is pre-assembled in an inexpensive manner as compared with previously known drums for type drum printers which were engraved from solid materials. (Cost of the fabricated type wheel drum of the present invention is approximately $\frac{1}{10}$ that of an engraved drum.) The drum 704 is fabricated from a plurality of double row type wheels 722, manufactured to very close tolerances, mounted, indexed and clamped on a drum shaft 723 in a manner now to be described.

As depicted in FIGURES 3-5, each type wheel 722 is made from a suitable high strength material capable of withstanding multiple print hammer blows and maintaining true circular shape under continual rotation. Steel, other presently known high strength metals and some plastics can be used. The wheel 722 has a central, disc shaped, thin web 724 apertured with lightening holes 725, an indexing hole 726 and balance holes 727 and 728.

The rim 730 of each type wheel 722 provides a peripheral T-flange carrying two axially spaced apart rows of raised printing symbols, such as letters, numbers, punctuation, etc., each pair of side by side raised symbols being identical and disposed with their center lines extremely accurately equidistant from the web center plane and also accurately equidistant from the nearest adjacent edge of the rim 730, as shown by representative actual values on FIGURE 5. The edges of rim 730 are flat and are accurately disposed in parallel planes normal to the wheel axis. As clearly depicted in FIGURE 5, the true axial dimension of the rim T-flange 730 is 0.2000" which is the distance of space required for two standard teletypewriting symbols, and this dimension is held to an extremely close tolerance range of $\pm 0.0005"$. This tolerance value is necessitated to prevent a build-up of a 72 character line, space error in an assembled drum. If the center line spacing of each of the two rows of characters is maintained within tolerances of $\pm 0.003"$ the overall character space tolerance of each character relative to adjacent characters and of the entire line of characters will be well within the acceptable limits.

The five-unit Baudot code permits of thirty-two different code bit combinations and, using letters and figures shift functions, sixty-four characters can be realized. Accordingly, in the exemplary printer, sixty-four positions are provided around the periphery of each type wheel rim 730 and all characters are accurately located at specific angular positions. A layout portion of a wheel rim is seen in FIGURE 4.

To assure that all wheels 722 are assembled in proper indexed alignment with the adjacent wheel, an index slot 726 is made in the web 724 of each wheel, the slot center line being aligned with one and the same specific character on all wheels. The web center holes 731 of all webs are also accurately located and are dimensioned to provide a smooth guided coaxial fit on the drum shaft 723. By means of a suitable jig, the index slots 726 are aligned before and during torqueing of the drum assembly into clamped assembly, as will be now described.

Going back to FIGURE 2, an intermediate length 733 of drum shaft 723 is dimensioned to fit the center holes 731 of the type wheels 722. Both ends of the intermediate shaft section 733 are threaded as indicated at 734. A suitable number (36 or 38) of wheels 722 are placed on the shaft 723, indexed to align the same characters on all wheels and clamped together by two end clamping plates 735, adjacent spacers 736 and nuts 737, the latter being threaded and torqued very tightly on the threaded ends of the intermediate shaft section 733. (Note: with 38 wheels, the spacers 736 are omitted.) The center holes 738 of clamp plates 735 are the same size as the type wheel center holes 731 and also have a smooth coaxially locating fit on drum shaft intermediate portion 723. The outer periphery of each clamp plate 735 is provided with a right angled annular flange 737 which faces the stack of type-wheels and fits with a slight radial clearance coaxially within the circumscribing axially extended end flange of the rim T-flange 730 of the adjacent type wheel 722, abutting the wheel web 724 in annular contact. This fit transfers an even annular clamping force from plates 725 to the webs of the end wheels and thence to the outer periphery of each of the end type wheels of the assembled drum 704 and thus, the clamping pressure is evenly transferred through the flat abutting rim edges of all adjacent typewheels 722. This clamping pressure is all that is required to hold all typewheels in true indexed alignment. Both sets of clamping plates 735, spacers 736 and nuts 737 are locked together, after the clamping pressure is achieved, by a roll pin 740.

A left hand bearing retainer assembly 742, which carries a bearing 743 in a socket 744, is placed over the left hand reduced diameter end 745 of the drum shaft 723 with the inner race of the bearing 743 against a shoulder 746 formed between the shaft end 745 and the shaft intermediate section 733. A somewhat similar right hand bearing retainer assembly 747 and shaft bearing are placed over a right hand reduced end portion 776 of the drum shaft 723. Right hand bearing assembly 747, as shown in FIGURE 2, includes an integral clock head mounting plate 748, which serves to rigidly mount the printer clock monitor heads 180, 184 and 186, etc.

Before the hubs 749 and 750 of respective bearing retainers 742 and 747 are clamped in sockets on respective printer frame end plates 720 and 721 by clamping blocks 751 and 752, left and right hand record medium feed wheels 753 and 754, with associated ring gears 755 and 756, are placed on external bushing sleeves 757 and 758 integral with the associated bearing retainers. The feed wheel gears 755, 756, are clamped to the respective feed wheels 753 and 754 by screws and split, annular ring 70 clamping plates 759 which fit into and ride in grooves 760 in the bearing retainer body to axially maintain the feed wheels 753 and 754 in position adjacent each end of the drum 704.

A rubber O-ring 761 is stretched over the periphery of 75 each feed wheel 753, 754 and fitted into half circle

grooves 762 in the periphery of its feed wheel, and then cut or ground down almost even with the feed wheel periphery to serve as a friction band to engage and line feed the page record medium, by means to be hereinafter described. If desired, the O-ring 761 may be cemented in the groove 762 but it is not necessary. Note, the feed wheels are now rotatably mounted on the bearing retainers which will be clamped in adjacent printer frame end plates 720 and 721 and the drum 704 is rotatably mounted relative to the bearing retainers, completely independent of the record feed wheels 753 and 754.

Drum drive.—Assembled in the frame, as seen in FIGURE 2, the left hand drum shaft end 745 projects beyond the bearing retainer 742 and a gear 770 is non-rotatably secured thereto by set screws 771. The printer motor (not shown) is mounted on the inside of frame plate 720 with its shaft 772 projected through the plate and carrying a drive gear 773. A gear tooth drive belt 774 meshes with motor gear 773, drum gear 770 and a carriage return clutch input gear and when the printer motor is energized the drum 704 will continually rotate.

The clock wheel 706 is non-rotatably secured to the right hand drum shaft end 776, and has peripheral reference notches 777 properly located relative to the angular positions of the print characters on the drum 704.

The clock wheel 706 rotates with the print drum 704 and as it rotates, the moving notches vary the reluctance of bar type magnets located in the clock monitor head coils 180-186 inducing appropriate current pulses into associated transistor amplifiers, as described in the aforementioned parent application.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. In a data processing drum printer:

a fabricated multiple character print drum having lines of raised type symbols across its cylindrical periphery, said drum being fabricated from a plurality of coaxial typewheels, each typewheel comprising:

an outer peripheral, axially flanged, circular rim, and

a thin intermediate web portion integral with and circumscribed by said rim; said outer peripheral rims of adjacent typewheels axially abutting each other and

means clamping all typewheels together in coaxial relationship and maintaining them in coaxial and predetermined angular position relative to each other; said clamping means exerting an axially directed pressure on the plurality of typewheels causing an axially directed pressed abutment between the peripheral rims of adjacent typewheels.

2. A print drum as defined in claim 1, wherein said web portion of every typewheel includes means accurately located relative to a specific predetermined angular location of said raised type symbols enabling accurate angular assembly of said plurality of typewheels.

3. A data processing drum printer print drum as defined in claim 1 wherein each one of said lines of raised type symbols has similar type symbols.

4. A data processing drum printer comprising:

a fabricated multiple character print drum having lines of similar raised type symbols across its cylindrical periphery parallel to the drum axis, said drum being fabricated from a plurality of typewheels, each typewheel having:

a flanged outer peripheral annular rim having a T-shape in radial cross section, and a thin coaxial locator web portion; the outer rims of adjacent typewheels axially abutting each other;

means coaxially clamping all typewheels together and maintaining them in indexed position by exerting axial clamping pressure through said typewheel peripheral flanges; and the width of the rim flange on each typewheel being made to equal dimensions in all typewheels, held to a close manufacturing tolerance on the order of +0.0005 inch.

5. In the print drum as defined in claim 4, each typewheel web portion being centrally apertured to provide a coaxial locator and having an eccentric aperture with edge means accurately located relative to said type symbols to enable accurate angular assembly of said plurality of typewheels.

6. A drum printer print drum having an axis and comprising: a plurality of individual rings, each ring being a print wheel having an inner radial disc-like web with an outer periphery and having printing symbol elements located around said outer periphery, said rings assembled

25 as a laminated drum with at least the major extent of said radial webs of adjacent ones of said rings being spaced apart; said rings having abutment portions extending axially from said webs and disposed closer to said outer peripheries than to said drum axis with said abutment

30 portions on adjacent ones of said rings being in pressed engagement with each other; and clamping means engaging and exerting opposed force on the ones of said rings constituting the end rings in said drum thereby transmitting axially directed pressure through said rings

35 at said abutment portions to facilitate maintenance of said rings in a predetermined position relative to each other with lines of said printing symbol elements extending across the outer peripheral surface of said laminated drum.

40 7. A drum printer print drum as defined in claim 6, wherein said clamping means comprise clamping end plates, one of which is located at each end of said plurality of rings.

8. A drum printer print drum as defined in claim 7, 45 wherein said clamping end plates engage and apply clamping pressure adjacent the outer periphery of each end ring.

9. A drum printer print drum as defined in claim 6, 50 wherein said printing symbol elements are raised type symbols.

10. A drum printer print drum as defined in claim 6, wherein each ring is made from lightweight material and includes a plurality of lightening holes.

11. A drum printer print drum as defined in claim 6, 55 wherein each ring has a T-shaped radial cross-section with the circular peripheral portion carrying the printing symbol elements constituting the cross flange of the T-shaped section.

12. A drum printer print drum as defined in claim 11, 60 wherein said printing symbol elements are raised type symbols.

13. A drum printer print drum as defined in claim 11, 65 wherein said flanges constitute said abutment portions, each of said rings

has identical dual rows of all desired character symbols to be printed by the printer, the center lines of axially aligned identical characters in said dual rows are accurately spaced apart a predetermined distance and are also closely accurately spaced from the adjacent edges of the peripheral flange one-half of that predetermined distance, and the axial widths of said peripheral flanges of all of said rings are maintained to the same dimension with an extremely minute tolerance.

14. In a data processing drum printer: a multiple character print drum, said drum being assembled from a plurality of coaxial typewheels, each typewheel including a radially extending web having a center hole, raised type symbols at the periphery of said web, and axially extending flange means integral with said web and spaced radially outward a substantial distance from said center hole, said flange means of adjacent typewheels being in pressed abutment with each other, and clamping means transmitting axially directed clamping pressure through said flange means causing axially directed pressure abutment between adjacent typewheels for facilitating maintenance of said typewheels in predetermined alignment relative to each other.

15. A drum printer print drum as defined in claim 14, wherein the sole place of contact between adjacent typewheels is at said flange means.
